(57) **CLAIM**

The ornamental design for a wearable fitness monitoring device for measuring oxygen and carbon dioxide, as shown and described.

DESCRIPTION

2. Wearable fitness monitoring device for measuring oxygen and carbon dioxide

2.1 is top, front, left side perspective view of a wearable fitness monitoring device for measuring oxygen and carbon dioxide showing the new design;

2.2 is a front view thereof;

2.3 is a rear view thereof;

2.4 is a right side view thereof;

2.5 is a left side view thereof;

2.6 is a top side view thereof; and

2.7 is a bottom view thereof.
